UNITED STATES PATENT OFFICE.

JAMES P. KELLY, OF NEW YORK, N. Y.

CORD-TIP.

1,392,339.

Specification of Letters Patent.

Patented Oct. 4, 1921.

Application filed May 25, 1921. Serial No. 472,429.

To all whom it may concern:

Be it known that I, JAMES P. KELLY, a citizen of the United States of America, residing at New York city, New York county, N. Y., have invented a new and useful Cord-Tip, of which the following is a specification.

My invention relates to a tip or finishing piece for a cord, rope, or the like.

10 The main object is to provide a simple but inexpensive construction for gathering together and holding the ends of a cord, lacing, or rope. Another object is to provide a construction which may be applied 15 by anyone and removed when necessary.

The invention in its preferred form contemplates the use of a clamping member which engages the end of the cord, and a sleeve or ferrule for holding the clamping 20 member in place.

Figure 1 shows the fragment of an end of a cord with one form of tip in section.

Fig. 2 is a perspective view showing the clamping member separated and the sleeve 25 slipped along the cord.

Fig. 3 is a side view showing a modified form of head.

Fig. 4 is a perspective view of a modified form of head and clamp.

30 Fig. 5 is a side view showing a modified form of head and clamp with a sleeve in section.

Fig. 6 is a side view and partial section showing another modification.

35 Figs. 7 and 8 are sectional views of other modifications.

The cord, lacing or rope which, for convenience will herein be called the cord, is indicated by the reference number 10. The 40 clamp member has jaws 11—11 for engaging the end of the cord and an exposed head portion 12. The jaws are held in place by the sleeve 13, which is adapted to be slid over the ends of the clamping members.

45 The clamping members may have teeth, such as 14, adapted to stick into the end of the cord to prevent the cord being pulled out. These teeth preferably point toward the head so as to catch into the material of

50 the cord when tension is applied. The free ends 15 of the clamping members may also be tapered or bent inwardly somewhat, so as to increase the gripping effect on the cord and also so as to make it easier to pull the 55 sleeve on over the jaws from the position

of the sleeve shown in Fig. 2 to that shown in Fig. 1. The head preferably has a shoulder 16 serving as an abutment for the outer end of the sleeve 13. The outer surface of the jaws 11 or the inner surface of 60 the sleeve 13 may be roughened, if desired, to prevent the sleeve slipping off and releasing the jaws.

In the form shown in Fig. 3 the clamping member and head are formed in two 65 parts 12'—12''. In the form shown in Fig. 4, the head is in one piece, but there are three jaws 11'—11'—11' adapted to grip the end of the cord.

In the form shown in Fig. 5 the clamping 70 member 11'' is tapered, and the sleeve 13'' is correspondingly tapered so that a sleeve can only be slipped on from the outer end, after which the head 12'' is upset so as to prevent the sleeve from being drawn off. 75

In the form shown in Fig. 6, the head 12^a has a shank 11^a which fits in the end of the cord. The sleeve 13^a holds the end of the cord together and prevents the head 12^a and its shank from being drawn out. The 80 shank may have burs or teeth 14^a formed therefrom or attached thereto to prevent withdrawal of the shank and head.

In the form shown in Fig. 7 the clamping jaws 11^b are provided with grooves 17 and 85 the sleeve 13^b is adapted to slip over and cover the outer end of the jaws. The inner end of the sleeve has a bead, flange or projection 18 adapted to snap into the groove 17. By compressing the inner ends of the 90 jaws 11^b the sleeve may be released.

The form shown in Fig. 8 is somewhat similar to that of Figs. 1 and 2, but one or both of the jaws 11^c may be provided with a groove 19 to receive a projection 20 on 95 the inner end of the sleeve. This sleeve is adapted to be slid on from the outer end, and may be released by compressing the inner ends of the jaws.

It will be clear that any one of the devices of Figs. 1 to 4 may be disassembled by simply sliding the sleeve along the cord so as to release the clamping jaws. Obviously, a lace or cord may be shortened by cutting it off at the desired point and 105 re-applying the tip.

The construction shown in Fig. 5 has certain of the advantages of the prior constructions, but, of course, cannot so readily be removed or replaced.

The construction shown in Fig. 6 may be re-applied by simply sliding the sleeve back along the cord, spreading out the end of the cord, removing the head and shank of 5 the tip, and re-applying them.

Although I have shown the tip as circular in cross section, it is obvious that it may be of any other cross sectional shape, such as flat, oval or hexagonal. It should also 10 be understood that the plug or head may be of any shape and that the parts may be ornamented or embossed, if desired.

I claim:

1. A cord tip comprising, a member having a head and teeth pointing toward the 15 head and a sleeve adjustable longitudinally of the cord with relation thereto and having one end abutting against said head.

2. A cord tip comprising, clamping jaws 20 and a sleeve adapted to slide along the cord

to embrace said jaws and hold the same in place.

3. A cord tip comprising, a head, jaws extending therefrom, and a sleeve abutting against said head and holding said jaws in 25 place.

4. A cord tip comprising a head, a clamping member having teeth for gripping the end of a cord, and a sleeve for co-acting with the clamping member and teeth to 30 hold the end of a cord in place.

5. A cord tip device comprising a member having clamping jaws with interior means for engaging the end of a cord and preventing said jaws from slipping from 35 the end of the cord, and a sleeve surrounding said jaws but slidable with respect thereto, for holding said jaws in engagement with the end of the cord.

JAMES P. KELLY.
